FOLDING AWNING

Harvey L. Angus, Havre, Mont.

Application August 24, 1954, Serial No. 451,774

4 Claims. (Cl. 160—58)

This invention comprises novel and useful improvements in a folding awning and more specifically pertains to a folding awning of metallic composition having an improved mechanism whereby the operation of folding the roof of the awning will automatically effect the inward folding of sectional end panels of the awning.

The primary object of this invention is to provide a folding awning of a metallic character which shall utilize the forces of gravity to assist in the opening movement of the awning into its erected, operative position and to maintain it in the same.

A further object of the invention is to provide a folding awning of the character set forth in the preceding object which shall utilize the mechanical advantage of leverage in a linkage mechanism to facilitate the folding of the awning against the effects of gravity.

A still further object of the invention is to provide a metallic folding awning as set forth above which shall employ corrugated aluminum sheets to form the folding roof of the same.

A still further object of the invention is to provide a metallic folding awning in which there shall be provided a joint cooperative action between the upper and lower folding panels of the roof of the awning and folding sectional end panels of the awning.

A further object of the invention is to provide a mechanism for folding metallic awnings whereby sectional end panels of the awning may be folded inwardly under the roof panels when the folding operation of the roof is initiated.

Another important object in accordance with the immediate preceding object is to provide an adjustment to compensate for minor variations in the proper proportions and dimensions of the folded linkages of the awning frame to thereby facilitate the proper adjustment of the awning mechanism and to facilitate the correction of and to compensate for minor discrepancies of operation which may result from wear during the use of the awning.

Yet another object of the invention is to provide a folding metallic awning in which the end panels shall be composed of sections each directly hinged to one of the roof panels whereby the end panel section may be folded under the roof panel during the folding operation of the awning.

A still further object of the invention is to provide a folding metallic awning having each end panel composed of a pair of sections so shaped as to overlap each other when the awning is unfolded and ready for operation whereby to form an end panel assembly substantially closing the end of the awning; but associated as to fold compactly in overlapping relation under the folding roof panel sections.

These together with other objects and advantages which will become subsequently apparent reside in the details of construction and operation as more fully here-

2

inafter described and claimed, reference being had to the accompanying drawings forming a part hereof, wherein like numerals refer to like parts throughout, and in which:

Figure 1 is a perspective view of a folding metallic awning in accordance with this invention, the same being shown applied to a window opening and disclosed in its folded raised position when the awning is not in operation;

Figure 2 is a perspective view of the awning of Figure 1, but showing the same in its open or lowered position when the awning is erected for operation;

Figure 3 is a perspective view of the frame of the awning the same being shown in the lowered position of Figure 2, the roofing and end panels of the awning being omitted therefrom;

Figure 4 is a vertical sectional view taken upon an enlarged scale of the awning in its folded, raised position of Figure 1, and is taken substantially upon the plane indicated by the section line 4—4 of Figure 1;

Figure 5 is a vertical fragmentary sectional view taken upon an enlarged scale substantially upon the plane indicated by the section line 5—5 of Figure 2 and showing the position of the parts and mechanism when the awning is in its operative lowered position of Figure 2; and

Figure 6 is a group perspective view of two panels forming the sections of one of the folding ends of the awnings.

Referring now specifically to the accompanying drawings wherein like numerals designate similar parts throughout the various views, it will be seen that the foldable awning, designated generally by the numeral 10, is illustrated as mounted in operative relation to a vertical surface such as a window construction 12 with which it is desired to use the functions and advantages of the awning. As shown best in Figure 3, the foldable awning includes a folding frame assembly which is designated generally by the numeral 14 and which comprises upper and lower frame sections 16 and 18 respectively.

The upper section 16 is secured to the window assembly or any other vertical assembly upon which the awning is mounted as by hinges 20 and as shown best in Figure 4, the lower end of the upper section and the upper end of the lower section are hingedly connected together as by hinges 22 whereby the awning frame may be pivoted from its unfolded, lowered and operative position shown in Figure 3 to the raised or folded positions shown in Figures 1 and 4.

The upper and lower sections 16 and 18 are each covered by any suitable covering, and for the purposes of this invention a sheet of corrugated metal, such as aluminum or the like is preferably employed, the corrugated covering for the upper section being shown at 24 while that for the lower section is shown at 26. A pair of pivoted braces are provided to facilitate the folding and unfolding operation of the roof sections and to support the same in either their folded or unfolded positions. These braces, are longitudinally extensible, preferably comprising a rod-like member 30 which is hinged to a supporting bracket 32 mounted upon the vertical supporting surface in any desired position, and a member

34 pivoted as at 36 to the lower portion of the frame of the lower section 18 of the awning roof. An adjusting nut 38 upon the threaded extremity of the rod 34 serves to lock the end of the ladder in adjusted position in the internally threaded extremity of the member 30. By this means slight adjustments can be made in the length of the brace in order to secure the proper length of the same, in relation to the proportions and dimensions of the upper and lower sections of the awning roof and the position of the pivots 20 in order to effect the folding of the awning from its raised position of Figures 1 and 4 to its lowered position of Figures 2, 3 and 5.

In the awning illustrated, two braces have been shown, one at each end of the awning. It will be readily understood that any desired number of braces will be provided depending upon the length and width of the awning.

Various types of operators may be provided for effecting the folding movement of the awning between its upper and lower positions. Conveniently, the arrangement shown in Figures 4 and 5 may be provided, the same comprising a crankshaft extending through the window or wall opening with which the awning is associated, and having an operating handle 40 preferably disposed within the structure over which the awning is mounted, and having a pulley or windlass 42 on its extremity which extends outwardly of the structure. A cable 44 is secured to the windlass, and passing over guide pulleys 46 and 48, secured respectively upon the window assembly and to the underside of the framework of the upper section of the awning roof, is then secured at its extremity, as at 50, to the underside of the frame of the lower section of the awning roof.

In the arrangement as illustrated it will now be evident that tensioning of the cable will cause the lower end of the lower section to be moved closer to the upper end of the upper section, this resulting in a folding of the two sections about their connecting hinges 22, until the sections are folded upon each other as shown in Figure 4. During this folding movement of the two sections, the attachment of the lower end of the lower section to the braces causes the latter to move upwardly upon its pivot 32. It will be evident that the various links of the movable members will be so proportioned and their pivots will be so located as to permit and effect this folding movement from the arrangement of Figures 5, 2 and 3 to the upper, folded position of Figures 1 and 4. Any slight discrepancy in the proportions, either due to inaccurate manufacture, or to wear in the parts during use, can be compensated for by adjusting the length of the brace members 30 and 34.

It is, of course, understood that in some instances the folded awning may include no more than the structure previously described. Thus, the same may consist of merely the upper and lower roof sections with the above-described folding operation. However, it is generally preferred to provide end panels to close the open ends of the awning below the roof portion. For this purpose, there are provided at each end of the awning an end panel, the same consisting of a pair of sections 54 and 56. As shown in Figure 6, these sections are of different size and shape, for a purpose which will now be set forth. The end panel section 54 is adapted to underlie the upper roof sections 16 and for that purpose has an upper edge 58 which is substantially of the same length as the end of the upper roof section and is adapted to be hingedly secured to the underside of the roof section frame as by suitable hinges 60, hinge attaching apertures 62 being provided in the section 54 for that purpose. In a similar manner, the end panel section 56 is provided with apertures 64 whereby hinges 66 attached thereto may be employed to secure the upper edge 68 of the section 56 to the underside of the lower roof section. Thus, the two sections 54 and 56 are pivoted or hinged to the undersides of the upper and lower roof sections for swinging or folding movement therebeneath. Further, the edges 58 and 68 of the two end panel sections are disposed closely adjacent to and beneath the underside of the sections of the awning roof. At its end which is remote from the section 56, the section 54 has a vertical edge 70 which is adapted to be disposed closely adjacent the window assembly 12 or the vertical surface upon which the awning is supported to substantially close the space between the same and the lower side of the awning roof.

The two sections of the end panel are so proportioned that their lower edges 72 and 74 lie in substantially the same horizontal line or plane with the lower portion of

the lower section of the awning roof to thereby close the space at the end of the awning roof.

The adjacent edges of the panels 54 and 56, shown at 76 and 78, respectively, are disposed in overlapping relation. This relationship is indicated in Figure 5 in which it will be seen that the edge 78 overlies the panel 54 and its edge 76. It will now be seen that when the end panel sections 54 and 56 are swung about their hinges, they will move from their vertical, erected positions shown in Figures 2 and 5, to a position folded beneath the roof panels as will be understood from Figures 1 and 4.

In general, the force of gravity is relied upon to cause or assist in the unfolding or downward movement of the roof panels from their folded position of Figures 1 and 4 to their open position of Figures 2, 3 and 5; and to assist in the downward swinging movement of the end panel sections from their collapsed position in Figures 1 and 4 to their vertical, open positions of Figures 2 and 5. If desired, spring or other means could be provided to assist in any of these unfolding operations or movements of the awning parts. In order to cause the folding of the end panel sections to their collapsed or stored position beneath the roof panels, during the folding of the awning roof, a mechanism is provided interconnecting the end panel sections with the roof panel sections. This mechanism is shown more clearly in Figures 3-5 and comprises the linkage and pulley system. The linkage includes a pair of elements or members 84 and 86 which are pivotally connected at 88, and have their opposite ends pivoted as at 90 and 92 to the frame of the upper and lower sections of the roof. By comparing Figures 3 and 5 with Figure 4 it will be seen that the roof sections and their folding movement cause a corresponding pivoting actuation of the linkage members. Secured to the links at their pivotal connection 88 is one end of cables 94. These cables are entrained over pulleys 96 secured to the frame of one of the roof sections and thence passes through guide members 98 carried by the lower portion of the lower roof section, and has its other ends attached as at 100 to the lower edge of the end panel section 56 which lies outwardly of the other end panel section 54. Thus, when the cable is tensioned by actuation of the folding linkage members 84 and 86, the end panel sections 56 will be folded inwardly and due to the overlapping relationship with the end panel sections, also fold the latter inwardly.

The arrangement is such that upon the initial upward or folding movement of the roof section of the awning, the movement imparted to the linkage members 84 and 86 hereby will tension the cables and thus initiate the inward folding movement of the end sections of the awning, whereby a joint folding action is imparted to both the roof sections and the end sections. After the end sections have moved in a certain amount, further inward movement is unnecessary since the completion of the inward-folding of the sections of the end panels will be completed by the pressure of the folding roof panel sections thereon.

It will be of course understood that proper proportions and dimensions will be given to the various elements to effect this functions, but obviously the choice of these dimensions and proportions is in no way a limitation upon the principles of this invention. It will be evident that the distances between the pivot points of the upper and lower roof sections and the brace may be so selected as to secure a very rigid mounting of the awning in its opened position and constitute a positive limit to the downward opening movement of the awning.

From the foregoing, the construction and operation of the device will be readily understood and further explanation is believed to be unnecessary. However, since numerous modifications and changes will readily occur to those skilled in the art, it is not desired to limit the invention to the exact construction shown and de-

scribed, and accordingly, all suitable modifications and equivalents may be resorted to, falling within the scope of the appended claims.

What is claimed as new is as follows:

1. A folding awning comprising a roof having upper and lower sections and being movable between a raised, folded position and a lowered, opened position, means hingedly supporting the upper section by its upper portion for vertical swinging movement, means hingedly connecting the upper end of the lower section to the lower end of the upper section for relative swinging and folding movement, a brace pivoted at one end to the lower end of the lower section and at its other end supported for vertical swinging movement for joint movement with the roof, a foldable end hinged to said roof, said end comprising a pair of end sections each hinged to one of said roof sections at the outer edge and to the underside thereof for folding therebetween when said roof sections are folded into their raised and folded position, said end sections being independent of each other.

2. A folding awning comprising a roof having upper and lower sections and being movable between a raised, folded position and a lowered, opened position, means hingedly supporting the upper section by its upper portion for vertical swinging movement, means hingedly connecting the upper end of the lower section to the lower end of the upper section for relative swinging and folding movement, a brace pivoted at one end to the lower end of the lower section and at its other end supported for

vertical swinging movement for joint movement with the roof, a foldable end hinged to said roof, said end comprising a pair of end sections each hinged to one of said roof sections at the outer edge and to the underside thereof for folding therebetween when said roof sections are folded into their raised and folded position, said end sections being independent of each other, actuating means operatively connected to said roof sections and to said end sections for causing folding of said end sections upon relative folding movement of the roof section.

5 3. The combination of claim 2 wherein said actuating means mechanism connected to said end panel and operable by folding of the roof for folding said end panel under the roof, said mechanism including a pair of elements connected to relatively movable portions of the roof for actuation thereby.

10 4. The combination of claim 3 wherein said mechanism includes tension members fastened each to one of said elements and to said end panel.
